(57) **CLAIM**

The ornamental design for a pipe fitting set as shown and described.

DESCRIPTION

FIG. 1 is a perspective view of a first component of a pipe fitting set showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second component of the pipe fitting set;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the pipe fitting set where the first component is assembled with the second component;

FIG. 18 is another perspective view thereof;

FIG. 19 is a perspective view of the pipe fitting set where the first component is separated from the second component; and,

FIG. 20 is another perspective view thereof.

The broken lines in the drawings depict portions of the pipe fitting set that form no part of the claimed design.

1 Claim, 20 Drawing Sheets
